UNITED STATES PATENT OFFICE

LEON WEINSTEIN, OF ST. LOUIS, MISSOURI

WEAR-PLATE FOR SHOE-HEELS AND THE LIKE

Application filed May 31, 1930, Serial No. 457,724. Renewed December 10, 1931.

This invention relates to a certain new and useful improvement in wear plates for shoe-heels and the like and has for its object the provision, as a new article of manufacture, 55 of a wear-plate adapted for efficient interlocking or anchoring engagement with the shoe-heel.

And with the above and other objects in view, my invention resides in the novel features of form, construction, arrangement, and combination of parts hereinafter described and pointed out in the claims.

In the accompanying drawing,

Figure 1 is an inverted plan view of a heel 15 of a shoe equipped with a wear-plate embodying my invention;

Figure 2 is a fragmentary sectional view of the shoe-heel taken approximately on the line 2-2, Figure 1;

Figure 3 is a view similar to Figure 2, showing the wear-plate partially applied to the heel;

Figure 4 is a perspective detail view of the wear-plate; and

Figure 5 is a sectional view of the wear-plate taken approximately on the line 5-5, Figure 4.

Referring now more in detail and by reference characters to the drawing, which illustrates a preferred embodiment of my invention, my new wear-plate includes a main or body-portion A having preferably the arcuate somewhat crescent-shaped form and contour best seen in Figure 1 and constructed of any suitable relatively bendable metallic material, such as, for instance, steel, malleable iron, or the like. For purposes presently appearing, the plate A, as initially or originally constructed, is longitudinally convexly bowed, as best seen in Figure 3.

Upon its one or under face and along its margin, the plate A is provided with a depending acuminate wall 2, which along the rear of the plate preferably tapers in height 45 from the longitudinal center of the plate to its opposite ends; and longitudinally aligned and projecting from and at the opposite ends of the under face of plate A, is a pair of rigid hooks B, whose shanks 3 are originally disposed normal to the convexed curvature of

the plate A, and, hence, converge or incline inwardly towards each other. The hook-shanks 3 are preferably chisel-pointed at their outer end, as at 4, and barbed each with a recurved lateral point or bill 5 respectively oppositely presented outwardly of the bow of, and hence longitudinally parallel with, the plate-body A, the bills 5 being respectively spaced from the plate-body A suitably to provide, as may be said, a notch 6 therebetween.

Intermediate the ends of, and, preferably, punched out and inturned from, the plate-body A for depending therefrom, is a dart or prong 7, and, further, at its opposite ends, the 65 plate-body A is provided with respective preferably counter-sunk nail-receptive apertures 8.

In use, the plate A is applied at the desired location upon the outer face of the heel C 70 of the shoe, which, in the present instance, includes an outer lift 9 of rubber or like resilient material, nailed, as at 10, to the leather or wood body 11 of the heel, a relatively thin section 12 of penetrable sheet metal, fiber, or the like being flatwise interposed and fixed intermediate the heel-body 11 and its lift 9 for retaining engagement and co-operation with the plate A.

By means of a hammer or other suitable tool, driving pressure is applied through the plate A upon its hooks B, and the shanks 3 are driven into the heel C to penetrate substantially through the lift 9 and section 12 and, hence, more or less convergently or obliquely into the heel-body 11, the bow of the plate-body A then providing, when its ends are seated on the lift 9, a chordal space, as 13, therebetween, so that intermediately the body-member is uplifted from the heel, and the bills 5, in passing through the lift section 12, puncture the same with corresponding slots or apertures 14 wider than the shanks 3, which latter are, hence, laterally shiftable therein, as best seen in Figure 3, and I might add that the dart or prong 7 is partially driven into the heel at the same time. The plate A is then firmly beaten or flattened onto the heel C, whereupon the body A bends to reside flatwise on the lift 9, as shown in 100

Figure 2, and the shanks 3 shift laterally to locate their bills 5 under, and in anchoring or interlocking engagement with, the section 12, the shanks 3 then extending more or less 5 perpendicularly or in mutually parallel position relatively to the plate-body A, as also best seen in Figure 2.

And, concurrently, the acuminate wall 2 is driven into the lift 9 and the prong 7 into 10 the heel-body 11, as will be understood. I might add that the nails 10 are preferably arranged in an arcuate series along the outer margin of the heel C, and the nail apertures 8 are hence provided conformably for such 15 purpose, although not essential for securing the plate A to the heel of the shoe.

It will be observed that the more the shoe is employed in walking or the like, the more 20 effectually is the plate A flattened, and the bills 5 correspondingly the more firmly pressed into the heel-body 11 and under the retaining-section 12.

My invention hence greatly simplifies and 25 facilitates the application of wear-plates to shoes, and when so applied, the wear-plate is securely and efficiently anchored upon and interlocked with the heel-body. My new wear-plate is practical, dependable, and 30 advantageous in its intended use; and, further, provides an article that is neat, attractive and inexpensive in manufacture.

It will be understood that changes and 35 modifications in the form, construction, arrangement, and combination of the several parts of the plate may be made and substituted for those herein shown and described without departing from the nature and principle of my invention.

Having thus described my invention, what 40 I claim and desire to secure by Letters Patent is:

1. As a new article of manufacture, a wear-plate for shoes comprising a longitudinally bowed bendable body-member, and heel-engaging hooks projecting laterally from one face and at the opposite ends of the body-member, the shanks of the hooks extending in 45 converging relation and the bills of the hooks being disposed in opposed relation outwardly of the bow of the body-member.

2. As a new article of manufacture, a wear-plate for shoes comprising a longitudinally bowed bendable body-member, heel-engaging hooks projecting laterally from one face and at the opposite ends of the body-member, the shanks of the hooks extending in converging relation and the bills of the hooks being disposed in opposed relation outwardly of the bow of the body-member, and a prong projecting laterally from said one face of the body-member intermediate said hooks.

3. In combination with a shoe-heel including a body, an outer lift, and a retaining section interposed between said body and lift, 65 of a wear-plate including a longitudinally

bowed bendable body-member adapted for disposition upon the outer face of the lift, and rigid hooks projecting laterally from one face and at the opposite ends of said body-member and comprising shanks extending in converging relation and the bills of the hooks being disposed in opposed relation outwardly of the bow of the body-member, said hooks being adapted for penetration into and through said lift and section and on a flattening of 70 said body-member for plate-anchoring engagement at their bills with said section.

4. A shoe wear-plate comprising a metallic plate of approximate crescent-shaped contour, hook-shanks projecting lengthwise 80 from, and approximately at a right angle to, one face, and adjacent the opposite ends, of the plate, and bills on said shanks spaced by the shanks from the plate and having pointed ends presented outwardly in opposed relation toward the opposite ends of the plate.

In testimony whereof, I have signed my name to this specification.

LEON WEINSTEIN.
